Patented Feb. 12, 1924.

UNITED STATES PATENT OFFICE.

ALFRED M. ZIEGLER, OF NEWTON, MASSACHUSETTS.

GARMENT SUPPORTER.

Application filed January 14, 1922. Serial No. 529,376.

To all whom it may concern:

Be it known that I, ALFRED M. ZIEGLER, a citizen of the United States, and a resident of Newton, county of Middlesex, and State 5 of Massachusetts, have invented an Improvement in Garment Supporters, of which the following description, in connection with the accompanying drawings, is a specification, like characters on the drawings representing 10 like parts.

This invention relates to garment supporters such as garters and the object is to provide a construction of this nature which will be efficient, comfortable to wear and 15 durable and at the same time of attractive appearance. The invention will best be understood by reference to the following description of the illustrative embodiment thereof shown by way of example in the accompanying drawing, wherein:

Fig. 1 is a perspective of a garter with parts broken away; and

Fig. 2 is an enlarged section of one end of the garter on the line 2—2 of Fig. 1.

25 My invention finds a particular application in the type of garter illustrated in the drawing which is commonly known as a wide web garter, that is, the elastic band which encircles the leg is of relatively great width, 30 say an inch and a half or even more. Referring to the drawing, the garter shown may embody a so-called pad 3 from which depends the clasp 5 which is secured to the sock and to which is also connected the leg 35 encircling band. This pad 3 as shown in Fig. 1 may conveniently embody two thicknesses of material stitched together and between which the ends of the various parts fastened thereto are secured. The pad in 40 the form of the invention shown is of a general lozenge shape with truncated ends and the gracefully incurved lower edges.

45 Secured to one side of the pad 3 is a band 9 of elastic webbing adapted to encircle the leg and which may be provided with the usual adjusting buckle or slide 11. A fastening 13, herein shown as having an eyelet 15 of the key-hole slot type projecting therefrom, may be held by the looped back end of 50 the band which is secured by the buckle 11.

To hold the band 9 in its encircling relation about the leg a suitable attachment is provided which is disposed on a projection from the side of the pad 3 leaving the 55 pad unobstructed and of attractive appearance. Herein I show a short piece 17 of in-

extensible material such as light canvas sandwiched between the two parts of the pad and projecting from the side thereof opposite the side to which the band 9 is attached. Covering over this piece 17 is a piece of the same material which forms the band 9 and herein I have shown a doubled piece of elastic webbing enclosing the piece 17 and having its ends secured between the 65 parts of the pad 3, this construction providing for concealing the piece 17 from both sides and also making a smooth end for the tab which projects from the left hand side of the pad 3 viewing Fig. 1. A member of a 70 separable fastener adapted to cooperate with eyelet 15, herein a stud 21 mounted on a base plate 23, is secured to the member 15 and may be disposed on the outer face of the doubled over member 17, this construction 75 insuring that no metal will come in contact with the leg at the interior of the garter and permitting the use of a member of comparatively small dimensions. Thus, as shown in the drawing, the height of the entire member 80 21 is considerably less than the width of the garter. Herein the base plate 23 has an eye which receives the stitches 25 passing through the sides of the looped member 19 and through the inextensible member 17.

If a projecting tab such as is herein formed by the parts 17 and 19 were made solely of elastic webbing, such as the main band of the garter, the fastening element secured thereto, especially if of small size, 90 would pull unevenly on the webbing since the latter would give in the zone aligned with the fastening and the strain would not be transmitted throughout the width of the tab to the pad. In the present instance the 95 strain is taken up by the inextensible member 17 and is transmitted to the full length of the seam by which that member is secured to the pad 3. At the same time the garter presents to the eye a uniform appearance, 100 the parts of the leg band apparently being all of the same webbing and the appearance of the pad 3 is not in any way marred. The face of the pad 3 may be made of fine fabric such as silk and as the connection is 105 at the side of it no metal parts or rough fabric come in contact with the face of the pad to wear it.

While I have here shown a stud on the 110 face of the tab and secured to the piece 17 with which is engaged an eyelet on the band 9, it will be understood that within the

scope of my invention other means may be utilized for connecting the end of the band to the tab so that the strain is taken up by the inextensible piece 17.

5 I have explained in detail my invention as applied to a garter as shown in the drawing but it will be understood that the principles thereof find application in garment supporters of different construction. What 10 I claim as new and desire to secure by Letters Patent I shall express in the following claims:

1. A garter comprising a pad, an elastic band secured to one side of the pad and carrying an element of a separable fastener, a doubled loop of similar material, a piece of inextensible material within the loop, said piece and the ends of the loop being secured to the other side of the pad and a cooperating 20 fastener element having an engaging portion presented at the face of the loop within the margins thereof and secured to said piece.

2. A garter comprising a pad, an elastic band secured to one side of the pad and carrying an element of a separable fastener, a

short piece of inextensible material secured to the other side of the pad, a cooperating fastener element secured to said piece, and a covering for the said piece composed of the same material as the elastic band.

3. In a garment supporter, a joining element, an elastic web extending therefrom, a short piece of inextensible material extending therefrom in another direction, a covering for the said piece consisting of the same material as said web and a fastening device on the face on said covering and secured to said piece.

4. A garter comprising a pad, an elastic band secured to one side of the pad and carrying a fastening device, a short piece of inextensible material secured to the other side of the pad, a covering for said piece composed of the same material as the elastic band and means for releasably engaging the fastening device in strain transmitting relation to said piece.

In testimony whereof, I have signed my name to this specification.

ALFRED M. ZIEGLER.
